Primary Examiner — Bridget L Eland(74) *Attorney, Agent, or Firm* — McClure, Qualey & Rodack, LLP(57) **CLAIM**

The ornamental design for a wireless gateway as shown and described.

DESCRIPTION

FIG. 1 is a front perspective view of a wireless gateway showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings show portions of the wireless gateway that form no part of the claimed design.
